OLE A. STOEN,

ATTORNEY.

UNITED STATES PATENT OFFICE.

OLE A. STOEN, OF BALSAM LAKE, WISCONSIN.

SILO.

1,425,346.

Specification of Letters Patent. Patented Aug. 8, 1922.

Application filed September 2, 1920. Serial No. 407,821.

To all whom it may concern:

Be it known that I, OLE A. STOEN, a citizen of the United States, residing at Balsam Lake, in the county of Polk and State of

5 Wisconsin, have invented certain new and useful Improvements in Silos; and I do hereby declare the following to be a full, clear, and exact description of the invention, such as will enable others skilled in 10 the art to which it appertains to make and use the same, reference being had to the accompanying drawings, and to the letters and figures of reference marked thereon, which form a part of this specification.

15 The object of this invention is to provide a novel construction of silo, provided with means for elevating the ensilage and for dumping the same after elevation thereof.

With this object in view, the invention re- 20 sides, generally stated, in a silo having a vertically reciprocating carriage carrying a bucket, and means for automatically tilting the bucket at a predetermined point in the elevation of the carriage, so as to dump 25 the contents of the bucket.

The invention is clearly illustrated in the accompanying drawings which show a preferred form of embodiment of my inventive ideas. Briefly described:

30 Figure 1 is a view in elevation, largely in section, of a silo equipped with my improvements;

Figure 2 is a horizontal sectional view on the line 2, 2 of Figure 1, looking in the direction of the arrows, and

35 Figure 3 is a fragmentary view in elevation, partly in section, taken at right angles to Figure 1.

Referring now in detail to the drawings: 40 1 designates a silo which may be of any conventional construction and form, and preferably annular in horizontal section, and provided with a top 2, which may be conical, as shown.

45 Disposed in a vertical position inside the silo, and suitably spaced therefrom is a standard 3, preferably non-circular in cross section, and in this instance rectangular in cross section, and suitably secured against 50 movement at the bottom thereof, as by a spike, or pointed pin, 4, and suitably braced at the top as by a rod 5, suitably secured to, and carried by, the vertical wall of the silo.

55 Carried at the top of the standard 3 is a yoke 6, secured, as by means of bolts 7

to the standard, and forming a support for a pulley 8 on a shaft 9, projecting through the yoke 6.

Passing over the pulley 8 is a cable 10, 60 wound around a drum 11, carried by a bracket 12 toward the lower end of the standard 3, said drum being conveniently rotated in any suitable manner, as by a crank 13.

65 The other end of the cable 10 is secured to a carriage movable on the standard 3. The carriage may be of any suitable construction and in this instance comprises a sleeve 14, encircling the standard 3, and 70 carrying anti-friction rollers 15, 15, movable on opposite faces of the standard 3. Secured to the sleeve 14 is a bracket 16, to which is pivotally connected, as shown at 75 17, a bucket 18.

Secured to the standard 3, toward the top thereof, is a wire 19, bent to provide two parallel arms 20, 20, extending on a downward inclined and secured at their outer ends to the bottom wall of a discharge aperture 21 80 in the wall of the silo 1.

A slide, or chute 22, comprising a plate, as shown, is carried and supported by the arms 20, 20, in this instance by having the sides of said plate bent around the arms 20, 85 20, said slide 22 extending from the aperture, or discharge opening, 21 toward the standard 3, as shown in Figure 1.

Preferrably, the wire 19 passes,—as shown in Figures 1 and 2,—through a boss 23, carried by a sleeve 24, secured to the standard 3, toward the top thereof, as by means of a pin 25.

Suitable means are provided for automatically tilting the bucket 18 as the same 90 approaches the slide 22, and in this instance such means comprise a rod 26, passing through the sleeve 24 and bent to provide arms 27, 27, which are curved longitudinally, as shown in Figure 1, and secured at their 100 outer ends to straps 28, secured in turn to the side wall of the silo 1.

In operation, as the crank 13 is rotated, the drum 11 is revolved, winding up the cable 10 thereon, and pulling upward upon 105 the carriage supporting the bucket 18, which carriage, with the bucket, moves upward until the bucket top contacts with the inclined arms 27, 27 which constitute cams to tilt the bucket, as shown in Figure 1, toward the 110 slide 22.

Continued upward movement of the car-

riage with the bucket will cause the bucket to be fully tilted so as to dump the contents thereof onto the slide 22. As the slide 22 is inclined, the ensilage dumped thereon from the bucket 18 moves by gravity toward the aperture 21, from which it escapes.

What I claim to be new is:

1. The combination with a silo having an opening in one side adjacent to the top, of an upright guide positioned within the silo at the side opposite the opening, spaced inclined bars extending from the opening to the guide, a chute supported by the bars and extending from the opening but stopping short of the guide, a carriage mounted to travel along the guide, means to apply power to move the carriage, a bucket seated upon the carriage and proportioned to pass between the bars at the end of the chute, and a cam positioned to overturn the bucket upon the chute while between the bars.
2. The combination with a silo having an opening in one side adjacent to the top, of an upright guide positioned within the silo at the side opposite the opening, spaced inclined bars extending from the opening to the guide, a chute composed of sheet material having upstanding edges rolled about and supported by the bars and extending from the opening but stopping short of the guide, a carriage mounted to travel along the guide, means to apply power to move the carriage, a bucket seated upon the carriage and proportioned to pass between the bars at the end of the chute, and a cam positioned to overturn the bucket upon the chute while between the bars.
3. The combination with a silo having an opening in one side adjacent the top, of an upright guide positioned within the silo at the side opposite the opening, spaced inclined bars extending from the opening to the guide, a chute supported by the bars and extending from the opening but stopping short of the guide, a carriage mounted to travel along the guide and having a bracket

extending laterally therefrom at one side of the guide, means to apply power to move the carriage, a bucket seated upon the bracket and proportioned to pass between the bars at the end of the chute, and a cam proportioned to overturn the bucket upon the chute while between the bars.

4. The combination with a silo having an opening in one side adjacent to the top, of an upright guide positioned upon the silo at the side opposite the opening, spaced inclined bars extending from the opening to the guide, a chute supported by the bars and extending from the opening but stopping short of the guide, a carriage mounted to travel along the guide, means to apply power to move the carriage, a bucket seated upon the carriage and proportioned to pass between the bars at the end of the chute, and a cam comprising spaced curved rods overhanging the chute positioned to overturn the bucket upon the chute while between the bars.

5. The combination with a silo having an opening at one side adjacent to the top, of an upright guide positioned within the silo at the side opposite the opening, spaced inclined bars extending from the opening to the guide, a chute composed of sheet material having upstanding edges rolled about and supported by the bars and extending from the opening but stopping short of the guide, a carriage mounted to travel along the guide and having a bracket extending laterally therefrom at one side of the guide, means to apply power to move the carriage, a bucket seated upon the bracket and proportioned to pass between the bars at the end of the chute, and a cam comprising spaced curved rods overhanging the chute, positioned to overturn the bucket upon the chute while between the bars.

In testimony whereof I hereunto affix my signature.

OLE A. STOEN,
